DESIGN FOR A HANDLE FOR SPOONS, FORKS, AND SIMILAR ARTICLES.

No. 37,991.

Specification for Design.

Patented May 8, 1906.

Application filed April 5, 1906. Serial No. 310,181. Term of patent 7 years.

To all whom it may concern:

Be it known that I, CHARLES T. PAYE, a citizen of the United States, residing at North Attleboro, in the county of Bristol and State of Massachusetts, have invented a certain new, original, and ornamental Design for a Handle for Spoons, Forks, and Similar Articles, of which the following is a specification, reference being had therein to the accompanying drawings.

Figure 1 is a plan view of the obverse of a

spoon, fork, or similar article embodying my new design, showing in broken outline the tines of a fork; and Fig. 2, a like view of the reverse of the same.

I claim—

The ornamental design for a handle for spoons, forks, and similar articles, as shown.

CHARLES T. PAYE.
